UNITED STATES PATENT OFFICE

2,570,160

CLOSURE LOCK

Fred C. Schoch, Oak Park, Ill.

Application July 13, 1948, Serial No. 38,481

1 Claim. (Cl. 70—208)

1

This invention relates to improvements in locks for movable closures and refers particularly to a lock of the type described manipulatable by a handle which when in locked position is inaccessible to manipulate the lock.

One of the features of the present invention resides in a lock construction wherein the manipulatable handle therefor is maintained in an inaccessible position when the device is locked, the device being characterized in that it contains a minimum number of easily constructed, easily assembled parts.

Other objects and advantages of the present invention will be apparent from the accompanying drawings and followed detailed description.

In the drawings, Fig. 1 is a front view of a locker upon which my lock may be used.

Fig. 2 is an enlarged detail view of the lock handle.

Fig. 3 is a sectional view taken on line 3—3 of Fig. 2 showing the lock in locked position.

Fig. 4 is a similar view illustrating the lock in unlocked position.

Fig. 5 is an enlarged sectional view taken on line 5—5 of Fig. 3.

Fig. 6 is a sectional view taken on line 6—6 of Fig. 3.

Fig. 7 is a detailed sectional view taken on line 7—7 of Fig. 3.

Referring in detail to the drawings, 1 indicates a locker comprising a frame 2 and legs 3, a door 4 being mounted by means of hinges 5 upon one of the frame members. A lock assembly 6, comprising the concepts of my invention is mounted upon the door 4 of the locker 1. However, it is to be understood that my lock construction may be employed upon automobile doors, cabinet doors, automobile trailer doors or in general upon any type of movable closure and, hence, my invention is not to be limited to the specific environment shown and described.

The lock assembly 6 comprises a tubular housing member 7 having a flange 8 for mounting the same upon a closure 4. An aperture 9 is provided in the closure 4, the same being coaxial with the axis of the tubular housing 7. A face plate or guard 10 is mounted upon the front face of the door 4, the same being provided with an aperture 11 registering with aperture 9 in the door.

A bushing 12 is positioned within apertures 9 and 11 and the inner end of said bushing extends into the interior of the tubular housing 7. A tubular spindle 13 is positioned within bushing

2

12, the latter serving as a bearing permitting ready slidability and rotatability of the spindle. A handle 14 is rigidly mounted upon one end of the spindle 13, said handle, as will be hereinafter more fully described, being adapted to manipulate the latches employed to fasten the door in closed position.

The face plate 10 is provided with a recess 15 conforming in shape and slightly larger in size than the handle 14 whereby when said spindle is moved to its innermost position within the housing 7 the handle 14 fits snugly within the recess 15. A rectangular sectioned pin 16, preferably square in cross-section is adapted to be positioned within the housing 7 and within the spindle 13. In the interior of the spindle 13 and intermediate its length, a web 17 is positioned, the web preferably being integral with the spindle. Web 17 is provided with a rectangular aperture conforming with the section of pin 16, through which said pin passes, the pin being relatively slidable, but non-rotatable with respect to the spindle. A head 18 is carried upon one end of pin 16 to limit the outward movement of the pin with respect to the spindle.

The end of pin 16 protrudes through an aperture 19 which is enlarged with respect to the pin whereby the pin may rotate freely therein. A latch 20 is rigidly mounted upon the protruding end of pin 16 and is rotatable therewith, the latch 20 having an end 21 which is engageable with the frame member 2 to latch the door 4 when the lock assembly is in locked position. Intermediate the pin 16 and the end 21 of the latch 20 a rod 22 is pivotally secured to the latch and similarly a rod 23 is pivotally secured to an oppositely extending portion 24 of said latch. The opposite ends of the rods 22 and 23 are respectively connected to bolts 25 and 26 which engage with the top and bottom frame members when the door is latched, the arrangement being such that end 21 and bolts 25 and 26 may be disengaged from the frame 2 when pin 16 is rotated counterclockwise, as viewed in Fig. 5.

A coil spring 27 embraces pin 16 and is confined between the end of housing 7 and web 17, said spring normally tending to move spindle 13 outwardly. A keeper 28 mounted upon the inner face of the closure 4 extends in abutting relationship with respect to the end of pin 16 to prevent axial movement of said pin in an outwardly direction.

A transverse slot 29 (Fig. 6) is provided in the wall of housing 7 and a notch 30 is provided upon the corresponding side of spindle 16. A boss 31

is formed upon the flange 8 and is provided with internal threads whereby screw 32 may be threadedly positioned upon said boss. A bar 33 having an aperture 34 is adapted to be mounted upon boss 31, said boss being restricted in width adjacent its end so as to extend through the aperture 34 and function as a guide for reciprocal movement of bar 33. A lug 35 extends into an end of aperture 34 and functions as an anchoring pin for a coil spring 36 which is confined between an end of said aperture and boss 31. The head 37 upon screw 32 prevents lateral movement of the bar 33 with respect to the boss 31.

One end of the bar 33 is adapted to be positioned in slot 29, said bar being urged inwardly with respect to said slot by spring 36. The arrangement is such that when handle 14 and spindle 13 are in their innermost position, that is, when handle 14 is positioned in recess 15, the end of bar 33 which extends into slot 29 engages in the notch 30 in spindle 13 and prevents outward movement of the spindle. The opposite end of bar 33 is provided with an aperture 38 into which a cam member 40 is positioned. The cam member 40 comprises a portion of a lock 41 rotatably positioned in door 4, the lock being operably rotatable by means of key 42. Rotation of lock 41 and, hence, cam member 40 functions to move bar 33 axially to retract the end of said bar from notch 30 against the compression of spring 36.

In operation, when spindle 13 and handle 14 are in their outermost position determined by contact of web 17 with the head 18 upon pin 16, as shown best in Fig. 4, the bolts 25 and 26 and the latch 21 may be manipulated so as to disengage them from frame 2. Thus the door 4 can be opened or closed as the case may be. To lock the door, the handle 14 is so turned as to cause bolts 25 and 26 to engage the frame members 2 and then the handle is pushed inwardly until it is positioned in recess 15. At this time the end of bar 33 engages in the notch 30 and holds said handle in retracted position. The door then can-

not be opened except by means of key 42 by which means cam 40 may be rotated to slide bar 33 retracting the same from notch 30. Spindle 13 unrestrained by bar 33 will then move outwardly under the influence of spring 27 to position handle 14 in its outer operative position.

I claim as my invention:

A lock for a movable closure comprising a face plate adapted to be mounted upon the front of said closure, said face plate having a recess, a hollow housing adapted to be mounted upon the rear of said closure, said face plate and closure having connecting apertures which open into said hollow housing, a bearing sleeve in said closure aperture of greater length than the thickness of said closure, a hollow spindle slidably positioned in said bearing sleeve and said face plate aperture, a handle carried by said spindle and positionable in said recess, a pin slidably but non-rotatably connected to said spindle intermediate its length, a latch rigidly mounted upon said pin exteriorly of said housing, whereby said latch may be rotated by said handle, resilient means embracing said pin and bearing at opposite ends against said housing and an intermediate portion of said spindle respectively for urging said handle and spindle outwardly from said housing, said spindle being slidably supported by said bearing sleeve throughout the entire length of said bearing sleeve, and means for removably holding said spindle within said housing and said handle within said recess.

FRED C. SCHOCH.
